DI-PHASE PICKLING PROCESS

Anders Lennart Fredrik Hydén, Farsta, Sweden, assignor to Aktiebolaget Atomenergi, Stockholm, Sweden, a company of Sweden

Filed Sept. 26, 1960, Ser. No. 58,223

Claims priority, application Sweden Oct. 19, 1959
2 Claims. (Cl. 134—28)

This invention relates to pickling processes in general, i.e. processes of treating a metal object with a liquid, usually an acid, for affecting the surface of the metal, usually for removing metal oxides. The following specification refers to one particular pickling process, but it is evident to any body skilled in the art that the invention is not limited to that particular process.

In many pickling processes it is important that the objects to be pickled are transferred as rapidly as possible from the pickling bath to the subsequent rinsing bath. One example of such a process is the pickling of objects of zirconium and zirconium alloys in a mixture of nitric acid and hydrofluoric acid, for the purpose of removing from the surfaces of the objects such impurities as might otherwise produce damage due to corrosion. If such objects are lifted from the pickling bath in the conventional way and are then lowered into the rinsing bath, this must be done within a few seconds, because otherwise there are precipitated on the metal surface chemical compounds which are difficult to dissolve and to remove by rinsing, and which jeopardize the result of the pickling.

The present invention relates to a method which makes it possible to transfer the objects from the pickling bath to the rinsing bath directly and without transporting them in the air. The method of the invention is characterized by arranging a pickling liquid, having one specific weight, and a rinsing liquid, having a different specific weight, as stratified liquids, the lighter liquid forming a layer upon the heavier liquid, treating the object to be pickled in the pickling liquid and then transferring it into the rinsing liquid through the boundary layer between the two liquids.

The rinsing liquid is usually water, and water is lighter than the pickling liquid and is consequently stratified to form a layer upon the pickling liquid. It is possible, however, to stratify a lighter pickling liquid to form a layer upon a heavier rinsing liquid, for instance a comparatively concentrated sulphuric acid solution. In this case the object must not, of course, after having been rinsed, be lifted up through the overlaying pickling liquid layer, but must be removed from the apparatus while entirely surrounded by the rinsing liquid, for instance through a U-shaped chamber.

The pickling of objects of zirconium and its alloys may be carried out in a vertical cylinder. The lower portion of the cylinder is filled with an aqueous solution containing 39% by volume nitric acid having a specific gravity of 1.42, and 3.5% by volume of a hydrofluoric acid solution containing 52% by weight hydrofluoric acid. Water is stratified to form a layer upon the acid solution. The objects to be pickled are lowered through the open top end of the cylinder, through the water layer into the pickling liquid. When the pickling is finished the objects are lifted into the water layer where they are rinsed, for instance for a time of five minutes. The rinsing is

2

preferably made in running water. This can be arranged by adding water to the upper portion of the water column, and withdrawing water from the lower portion of said column, near the boundary layer between the pickling liquid and the rinsing liquid. If desired the pickling liquid, too, can be changed continually, by adding pickling liquid to one end of the pickling liquid column, and withdrawing pickling liquid from the other end of the column.

The above described process and the apparatus referred to are illustrated in the accompanying drawing which is a front view of the vertically disposed cylindrical vessel. Referring to the drawing, 1 is the rinsing zone, 3 is the pickling zone and 2 is the dividing zone in which the boundary layer between the pickling and rinsing liquids is maintained. Water is passed through the rinsing zone 1 by introducing fresh water at pipe 4 and withdrawing water contaminated with pickling liquid at pipe 5 which is provided with an open tube 6, preferably transparent, for observing the level of liquid in the zone 1. The overflow pipe 7 serves to prevent the liquid from overflowing the top of the vessel. The pickling zone 3 is double-walled or jacketed and is cooled by introducing water into the jacket through the pipe 10 and withdrawing it through the pipe 1. Pickling liquid is introduced through the pipe 9 and the three thermometers 8, 8, 8 serve for observation and control of the temperature of the pickling liquid. The apparatus may be used for either batch or continuous operation. In batch operation zone 3 is filled with acid up to zone 2 while a flow of water is maintained through zone 1. When the pickling acid becomes exhausted it is withdrawn through pipe 9 and zone 3 is then refilled with fresh pickling acid. In continuous operation acid is introduced continuously or intermittently through the pipe 9 and is permitted to rise to the level of the outlet of pipe 5 and to overflow therethrough along with the rinsing water from zone 1. Thus the boundary layer or mixed zone is maintained in the zone 2. No difficulty is encountered in keeping the rinsing layer and the pickling layer separate. In the continuous operation described above the upper boundary of the mixed zone will of course rise to the level of the outlet to pipe 5.

The pickling and rinsing liquids have a tendency of getting mixed with each other at the boundary layer between the two liquids, viz. by diffusion and by the movements caused by the objects passing through the boundary layer. It has been found, however, that it is possible to maintain the boundary between the two liquids sufficiently sharp for practical purposes. It is possible to control the height of the mixed zone, for instance by continually changing the pickling and rinsing liquids, as suggested above. In this case, the height of the mixed zone is determined by the distance between the two levels at which the pickling and rinsing liquids are withdrawn from the apparatus. The position of the mixed zone may be checked by means of bodies which float in the liquid and which have known specific weights between that of the pickling liquid and that of the rinsing liquid. These bodies place themselves at a level where the specific weight of the liquid is equal to that of the body.

What is claimed is:

1. A method of pickling objects of zirconium and zirconium alloys which comprises establishing a stratified bath consisting of a heavier bottom layer of an aqueous solution of nitric acid and hydrofluoric acid, a lighter top

layer of water and a boundary layer of a mixture of the liquids of said top and bottom layers, the liquids of said layers being miscible with each other in all proportions, supplying water to said top layer adjacent to the upper surface thereof and withdrawing water mixed with said aqueous solution from said top layer at a point adjacent to said boundary layer, and moving said objects from said bottom layer through said boundary layer into said top layer.

2. A method as defined in claim 1 in which said bottom layer is maintained by adding said solution thereto near the lower surface thereof. 10
